UNITED STATES PATENT OFFICE.

JARED B. McLANE, OF NORTH READING, MASSACHUSETTS.

POWER-HAMMER.

SPECIFICATION forming part of Letters Patent No. 703,787, dated July 1, 1902.

Application filed October 18, 1901. Serial No. 79,079. (No model.)

To all whom it may concern:

Be it known that I, JARED B. McLANE, of North Reading, in the county of Middlesex and State of Massachusetts, have invented certain new and useful Improvements in Power-Hammers, of which the following is a specification.

This invention relates to power-hammers; and it consists in certain improvements thereto hereinafter described and claimed, having for their object to condense the spring portion of apparatus employing springs to connect the hammer or striker with its operating mechanism, to provide guides for the hammer which shall be more secure and inexpensive to apply and renew than prior constructions, and to provide a treadle mechanism which may be operated from various positions with respect to the machine and with equal facility in any of said positions.

Of the accompanying drawings, Figure 1 represents a front elevation of a power-hammer provided with my improvements. Fig. 2 represents a side elevation. Fig. 3 represents an enlarged section on the line 3 3 of Fig. 1. Fig. 4 represents an enlarged vertical section of the spring and connections. Fig. 5 represents a section on the line 5 5 of Fig. 1, showing the treadle mechanism in plan.

The same reference characters indicate the same parts in all the figures.

In the drawings, 1 represents the cast frame of the hammer. 2 is the anvil; 3, the hammer, mounted to slide in vertical guides, and 4 is the driving-shaft, mounted in bearings at the upper end of said frame. A constantly-running belt 5, normally loose on a pulley 6, attached to the shaft, is controlled by a belt-tightener 7 on a lever 8, oscillated by the treadle mechanism, whereby the belt may be caused to grip the pulley and rotate the shaft 4.

Fixed to the front end of the shaft 4 is a fly-wheel 9, having a wrist-pin 10, connected by a link 11 with a spring 12, whose lower ends are attached to the outer ends of two pairs of links 13 13, which suspend the hammer 3 at their inner ends. The links are pivoted to a single pintle 14, passing through ears on the hammer. My improvement consists in making the spring 12 substantially in the shape of a lyre, its two depending arms

15 15 being outwardly and upwardly recurved or looped at 16 16 in their lower portions. The connection with the outer ends of the 55 links 13 13 is formed by pintles 17 17, passing through the links and surrounded by bushings 18 18, which occupy the bent or hooked extremities 19 19 of the spring-arms. This construction enables me to obtain a long 60 spring and long suspending-links, giving greater elasticity to the blow, but condenses the spring as a whole both longitudinally and horizontally, which, among other things, reduces the danger of the operatives being 65 struck by the spring.

The guides for the hammer are detachable from the frame 1 and are constructed as follows: On the frame 1 is formed a flat seat 20, against which the guide is held by two vertical rows of bolts 21 21. The guide comprises a gib-holder or base 22, having a planed outer face forming a bearing for the back of a dovetailed guide-engaging portion 23 of the hammer 3, and two gibs 24 24, mounted in said 75 holder and engaging the edges of said dovetailed portion. The bolts 21 pass through the gibs and holder and serve to secure the two together and to the seat 20 on the frame. Adjustment of the gibs in a horizontal direction is effected by means of adjusting-bolts 25 25, mounted in the holder 22, the gibs having elongated slots 26, occupied by the bolts 21, to permit such adjustment. The back of the gib-holder 22 and the face of 80 the seat 20 are left unplaned, and between the two are interposed two leather packing-strips 27 27. Other soft material—such as paper, fiber, lead, &c.—may be employed, although leather is preferred. The gib-holder finds its own bearing with respect to the seat 20 when the bolts are tightened, for the irregularities of each metal surface sink into the soft packing and a very secure joint is made. The guide may be removed 85 bodily from the machine, making the expense of replanning or renewal relatively small, and the construction is obviously such that the parts are few in number and may be easily assembled, taken apart, or adjusted. The 90 interposition of the leather packing avoids the expense of planed seating-surfaces for the removable guide, and the cushioning action of this packing increases the life of the 95 100

guide and prevents the bolts 21 from becoming loosened by the jarring of the machine.

A further improvement lies in the treadle construction, which I shall now describe.

5 28 represent two rocking treadle-frames having side arms 29 29 and cross portions 30 30 at the outer ends of the side arms. The frames have four hinge-bearings 31 31 at the inner ends of their side arms, and the side 10 arms of one frame are crossed with those of the other frame and pivotally connected thereto at the crossing by bolts 32 32, attached to one set of arms and occupying elongated slots 33 in the other set. One of the side 15 arms is connected by a rod 34 with the lever 8, which carries the belt-tightener 7. The belt-tightener may be actuated by stepping on any part of the treadle structure above the bolts 32 32, which will result in depressing 20 the rod 34 without any noticeable springing of either of the treadle-frames, such as is observable in single treadle-frames of the shape shown when the side away from the operating connection, such as 34, is stepped on.

25 I claim—

1. In a power-hammer, the combination of a hammer, a hammer-operating member, and a connection between the two including a pair of links suspending the hammer at their outer 30 ends, and a lyre-shaped spring device connected with the hammer-operating member

and having two depending spring-arms formed with outwardly and upwardly curved terminal portions connected to the outer ends of the links.

2. In a power-hammer, the combination of a frame having a seat for a guide, hammer-operating means mounted on said frame, a hammer, a guide therefor, having an unplaned back, bolts detachably securing the 40 guide to said seat on the frame, and a soft packing interposed between the guide and said seat.

3. In a power-hammer, the combination of a frame having a seat for a guide, hammer-operating means mounted on said frame, a hammer having a dovetailed guide-engaging portion, a guide for said hammer comprising a gib-holder engaging the back of said dovetailed portion of the hammer, gibs mounted 50 in said holder and engaging the edges of said dovetailed portion, and bolts passing through said gibs and gib-holder and detachably securing the same together and to said seat on the frame.

In testimony whereof I have affixed my signature in presence of two witnesses.

JARED B. McLANE.
